O. F. AALBUE,
CHEMICAL FIRE EXTINGUISHING DEVICE,
APPLICATION FILED APR. 21, 1916.

1,220,162.

Patented Mar. 27, 1917.

Inventor
Oluf F. Aalbue,
By his Attorney
Edgar Gates & Co.

UNITED STATES PATENT OFFICE.

OLUF F. AALBUE, OF BROOKLYN, NEW YORK.

CHEMICAL FIRE-EXTINGUISHING DEVICE.

1,220,162.

Specification of Letters Patent. Patented Mar. 27, 1917.

Application filed April 21, 1916. Serial No. 92,619.

To all whom it may concern:

Be it known that I, OLUF F. AALBUE, a citizen of the United States, and residing at Brooklyn, in the county of Kings and State of New York, have invented certain new and useful Improvements in Chemical Fire-Extinguishing Devices, of which the following is a specification, such as will enable those skilled in the art to which it appertains to make and use the same.

This invention relates to what are known as chemical fire extinguishing devices or apparatus, and the object thereof is to provide a device or apparatus of this class in which carbonic acid gas under high pressure is used as a chemical element for the purpose specified; a further object being to provide an improved container for the carbonic acid gas and improved means for filling said container with the said gas and discharging said gas from the container and the mingling thereof with the other element or elements employed.

The invention is fully disclosed in the following specification, of which the accompanying drawing forms a part, in which the separate parts of my improvement are designated by suitable reference characters in each of the views, and in which:—

Figure 1 is a sectional side view showing the main part of a chemical fire extinguishing apparatus made according to my invention with the carbonic acid gas container in full lines;

Fig. 2 a similar view showing the carbonic acid gas container in section and with parts of the device or apparatus in a different position;

Fig. 3 a view similar to Fig. 2 on an enlarged scale but showing only those parts of the device or apparatus connected with the carbonic acid gas container and showing said container empty; and,

Fig. 4 a view similar to Fig. 3 but showing the container filled and the parts in the position they assume when said container is filled.

In the practice of my invention I provide a suitable tank or container *a*, the top of which is provided with a large central aperture or opening *a*² around which is a collar *a*³ provided with an exterior thread *a*⁴ and an inwardly directed top flange or rim *a*⁵.

Suspended from the top of the flange or rim *a*⁵ is an openwork strainer tube *b* preferably composed of wire mesh and provided

with a top flange through which are passed screws *b*² whereby said strainer tube is secured to the flange *a*⁵ of the collar *a*³, and the strainer tube *b* is adapted to receive the carbonic acid gas container *c* which is made in the form of a tube and composed of sheet metal capable of resisting a high degree of pressure, and the top of which is closed by a plug *d* which is screwed thereinto and provided with a raised neck portion *d*² having a closure cap *d*³ which is screwed thereonto and in which is placed a thin copper disk or washer *d*⁴ above which is preferably placed a packing disk *d*⁵ of any suitable material, and the neck *d*² of the plug *d* is provided with a central vertical bore *d*⁶ and the cap *d*³ and packing disk *d*⁵ with similar bores *d*⁷ which register therewith.

In the bottom of the plug *d* is a conical chamber *d*⁸ in which is placed a vertically movable valve *e*, and the bottom wall of the plug *d* is provided with radial pins or similar devices *e*² which project into the bottom of the chamber *d*⁸ and on which the valve *e* rests when the device or apparatus is not in use.

The valve *e* is provided with a vertical tubular stem *e*³ which is movable through the bore *d*⁶ of the plug *d*, and in the bottom of which are ports *e*⁴ any desired number of which may be employed, and these ports form a communication between the stem *e*³ of the valve *e*, and communicate with the chamber *d*⁸ in the bottom of said plug when said valve is in the position shown in Fig. 3, and said ports are closed when the valve is raised as shown in Fig. 4, and the top walls *d*⁹ of the chamber *d*⁸ form a seat for the valve *e*.

The collar *a*³ of the tank or container *a* forms a neck which is provided with a closure cap *f* having a skirt member *f*² provided with an interior thread which corresponds with the thread *a*⁴, and said cap is provided with a packing gasket *f*³ and with outwardly directed handle members *f*⁴ by which it may be manipulated, and said cap is also provided with a raised and threaded neck *f*⁵ having a threaded closure cap *g* in which is placed a packing *g*², and a plunger rod *h* is passed downwardly through the cap *g*, the neck *f*⁵ and cap *f*, and through the packing disk or gasket *f*³ into the upper end portion of the strainer tube *b*, and said plunger rod is provided at its upper end with a handle *h*², and at its lower end with a

collar, nut or similar device h^3 which forms a head below which is a central downwardly directed and tapered punch device h^4 .

The foregoing covers the structural features of my improvement, and the operation will be readily understood from the following statement thereof taken in connection with the accompanying drawing.

It will be understood that the main tank 10 or container a is provided with the usual discharge tubes or devices and, in practice, the gas container c is filled with liquefied carbonic acid gas under approximately one thousand pounds pressure, and this operation 15 may be performed in the usual or any desired manner. After the gas container c has been filled and inserted into the strainer tube d , water or any other desired liquid substances may be poured into the tank a until said tank is filled, or partially filled, after which the cap f with the plunger rod h and the packing disk or gasket f^3 is 20 screwed into position as shown in Figs. 1 and 2 to close the tank a and in the normal 25 position of the parts when the apparatus is ready for use as shown in Fig. 1, the plunger rod h is in the position shown in said figure with the tapered punch device h^4 supported slightly above the cap d^3 of the gas container c , and whenever it is desired to use the apparatus the plunger rod h is forced 30 downwardly, and in this operation the punch device h^4 punctures the copper disk d^4 and the gas in the container c escapes 35 and mingles with the liquid contents of the tank a in the usual manner.

Although, I have described my improvement as particularly designed for use, or for the use of carbonic acid gas in a liquid 40 form, my invention in its structural features is not limited to the use of this gas and other elements having somewhat similar qualities may be used in the container c .

It will also be understood that in the operation 45 of filling the gas container c the valve e must be held in its depressed position as shown in Fig. 3, and when the cap d^3 is screwed on after the gas container has been filled, said cap holds said valve in the 50 said position, and when the disk d^4 has been punctured, as described, the contents of the gas container flows out around the valve e through the ports e^4 and out through the tube or sleeve e^3 into the strainer tube b .

Having fully described my invention, what I claim as new and desire to secure by Letters Patent is:

1. In an apparatus of the class described a gas container provided at one end with a 60 detachable closure device in the bottom of which is a valve chamber, said closure device being provided with a central vertical

bore which communicates with said chamber, and a valve mounted in said chamber and provided with a tubular sleeve which 65 passes through said bore and is movable therein, means for supporting said valve below its seat, and a threaded apertured cap for the closure device, said cap being provided with a puncturable disk which closes 70 the tube or sleeve of the valve when said cap is screwed on and with a central aperture which corresponds with the bore of the valve tube or sleeve.

2. In an apparatus of the class described, 75 a tubular gas container provided at one end with a closure plug in the bottom of which is a conical valve chamber, said closure plug being provided with a central vertical bore which communicates with said chamber, a 80 conical valve supported in said chamber and having a tubular stem which passes upwardly through said bore and is movable therethrough and provided adjacent to the valve with ports or passages, and a threaded 85 apertured cap adapted to be screwed onto the closure plug and provided with a puncturable metallic disk adapted to bear on the valve stem, said cap being provided with a central port which corresponds with the 90 bore of the valve stem.

3. In a liquefied carbonic acid gas container having a discharge port, a valve device adapted to open and close said port, means for supporting said valve device in 95 an open position when the container is empty, and means for holding said valve in an open position when the container is full, said last named means serving as a closure for said container. 100

4. In an apparatus of the class described, a liquid carbonic acid gas container, a valve mounted in said container and normally closed by the pressure of the contents thereof, a closure device for said container, and 105 means governed by said closure device for holding said valve in an open position.

5. In an apparatus of the class described, a container one end of which is provided with a discharge port, a valve mounted 110 therein, a cap detachably connected with the ported end of said container, and a puncturable disk mounted between said cap and said valve and adapted to hold said valve in an open position, said disk serving as a closure 115 for said container.

In testimony that I claim the foregoing as my invention I have signed my name in the presence of the subscribing witnesses this 19th day of April, 1916.

OLUF F. AALBUE.
